Primary Examiner—Stella Reid*Assistant Examiner*—C. Tuttle(74) *Attorney, Agent, or Firm*—Cislo & Thomas LLP(57) **CLAIM**

The ornamental design for a garden stake, as shown and described herein.

DESCRIPTION

FIG. 1. Is a right side elevational view of my garden stake with the left side elevational view being the mirror image thereof;

FIG. 2. Is a top plan view thereof;

FIG. 3. Is a bottom elevational view thereof;

FIG. 4. Is a front elevational view thereof; and,

FIG. 5. Is a rear elevational view thereof.

The stake is shown partially broken away in FIGS. 1-3 to indicate indeterminate length of the spring and shaft elements thereof.
